(57) **CLAIM**

The ornamental design for a housing for use with a process sensor, as shown and described.

DESCRIPTION

FIG. 1 is a right side elevation view of one embodiment of the housing for use with a process sensor (the left side view is a mirror image). The dashed lines represent a raised flat to accommodate an opening in the housing to accommodate cable conduit that can be located anywhere on the top of the housing.

FIG. 2 is a front elevation view of one embodiment of the housing for use with a process sensor. The dashed lines represent potential openings in each side of the housing to accommodate cable conduits (generally, only one top opening will be built in the housing).

FIG. 3 is a back elevation view of one embodiment of the housing for use with a process sensor.

FIG. 4 is a bottom elevation side view of one embodiment of the housing for use with a process sensor. The dashed lines represent an opening in the housing to accommodate cable conduit and that can be located anywhere on the top of the housing; and,

FIG. 5 is a top elevation view of one embodiment of the housing for use with a process sensor.

The structures shown in broken lines in the drawings are not part of the claimed design.
